UNITED STATES PATENT OFFICE

2,435,230

REGENERATOR FOR OPEN HEARTHS
AND THE LIKEJohn F. McLimans and Lewellyn L. Ausland,
Duluth, Minn.

Application December 15, 1944, Serial No. 568,354

2 Claims. (Cl. 263—15)

1

This invention relates to improvements in regenerators for open hearth furnaces and the like, and more particularly to improvements in the distribution of air to be heated therethrough.

It is among the objects of the present invention to provide a system for injecting air evenly into regenerators. It is another object to prolong the life of regenerators. It is a further object to provide better combustion in open hearth furnaces and the like.

The foregoing and further objects will be apparent from the specification and drawings, wherein:

Figure 1 is a horizontal view partly in section of a regenerator embodying our invention;

Figure 2 is a vertical section on line II—II of Figure 1;

Figure 3 is an end view, partly in section, along the lines III—III of Figure 2; and

Figure 4 is a side view, partly in section, of a flue showing the ports therein.

Referring more particularly to the drawings, the letter A designates a regenerator for an open hearth furnace or the like composed of two chambers 2 and 4 having checkerbrick 6 therein supported by arches 8 on rider walls 10.

Hot gases from the combustion chamber of a furnace, such as an open hearth (not shown), are admitted to the chambers 2 and 4 through ports B and B' and are withdrawn therefrom through openings C and C', into flue D and stack E. Ports B and B', also function to withdraw heated air from the chambers 2 and 4 to support combustion in the furnace chamber (not shown).

In accordance with the teachings of the present invention, air to be heated in the checker chambers 2 and 4, instead of being admitted thereto through openings C and C', is evenly distributed therethrough in the following manner. Flues 12 are provided in the rider walls 10 from which ports 14 open into the respective chambers 2 and 4 at spaced points throughout the width thereof. The flues 12 are connected to a manifold 16 by risers 15 and in turn the manifold 16 is connected to a compressor and pumping station 18.

In order to provide an even distribution of the air throughout the chambers 2 and 4, the ports 14 are progressively enlarged toward the rear-

2

ward side of the chambers, being smallest at the side nearest the manifold 16.

Dampers 20 and 22 are disposed on either side of the pumping station 18 to close it off from the manifold and flue arrangement when the regenerator is being heated by passing exhaust gases therethrough. When air is to be passed through the checker chambers 2 and 4, the valve 20 is opened so that compressed air from the 10 station 18 will be passed through the manifold 16, risers 15, flues 12 and ports 14, and thereby be evenly distributed throughout the chambers. The heated air flows therefrom to the combustion chamber (not shown) through ports 15 B and B'. It is understood that while air is being heated by being passed through chambers 2 and 4, similar chambers (not shown) are being heated by passing exhaust gases therethrough. During this time, the damper 22 is closed to shut 20 off the pumping station from the exhaust gases.

While we have shown and described one specific embodiment of our invention, it will be understood that this embodiment is merely for the purpose of illustration and description and that 25 various other forms may be devised within the scope of our invention, as defined in the appended claims.

We claim:

1. A regenerator comprising a chamber, 30 checkerwork contained in said chamber and rider walls extending across said chamber for supporting said checkerwork, means for evenly distributing air to be heated through said checkerwork, said means comprising flues in said rider walls and ports opening therefrom at spaced points across the width of said chamber, and means for supplying air under pressure to said flues, said means comprising a manifold connected to a source of air under pressure and a 35 plurality of risers having a smaller diameter than said manifold connecting said flues to said manifold.

2. A regenerator comprising a chamber, 40 checkerwork contained in said chamber and rider walls extending across said chamber for supporting said checkerwork, means for evenly distributing air to be heated through said checkerwork, said means comprising flues in said rider walls and ports opening therefrom at spaced 45 points across the width of said chamber, said

ports being progressively larger toward the rear of said chamber, and means for supplying air under pressure to said flues, said means comprising a manifold connected to a source of air under pressure and a plurality of risers having a smaller diameter than said manifold connecting said flues to said manifold.

JOHN F. MCCLIMANS.
LEWELLYN L. AUSLAND.
